ELECTRONIC CABINET

Lawrence J. Fay, Elgin, Ill., assignor to Equipto Electronics Corporation, Naperville, Ill., a corporation of Illinois

Filed Aug. 11, 1961, Ser. No. 66,313

Term of patent 7 years

(Cl. D26—5)

FIGURE 1 is a front perspective view of an electronic cabinet having a reversible writing top illustrated in sloped position showing my design;

FIGURE 2 is a perspective view of the design shown in FIGURE 1;

FIGURE 3 is a side view of the cabinet shown in FIGURE 1 only with the writing top inverted illustrating the work writing top in a horizontal position;

FIGURE 4 is a perspective view of the design shown in FIGURE 3; and

FIGURE 5 is a front perspective view of the cabinet on a larger scale, the work writing top thereof having been omitted for convenience of illustration.

The cabinet side not shown is substantially the same as the side shown and the back is conventional.

I claim:

The ornamental design for an electronic cabinet, as shown and described.
